UNITED STATES PATENT OFFICE.

ROSS A. WORKMAN, OF TULSA, OKLAHOMA, ASSIGNOR TO WORKMAN SHEET METAL COMPANY, OF TULSA, OKLAHOMA, A FIRM COMPOSED OF SAID ROSS A. WORKMAN, EARL G. WORKMAN, AND C. M. HUFF.

RIVETING MACHINE.

Application filed April 8, 1924. Serial No. 705,041.

To all whom it may concern:

Be it known that I, Ross A. WORKMAN, a citizen of the United States, residing at Tulsa, in the county of Tulsa and State of Oklahoma, have invented certain new and useful Improvements in Riveting Machines, of which the following is a specification, reference being had therein to the accompanying drawing.

10 The present invention relates to riveting machines, and aims to provide a novel and improved machine for setting rivets in the standing seams of sheet metal roofs, such as are used on oil tanks, in order that the rivets 15 can be conveniently and efficiently swaged or crushed.

Another object is the provision of such a machine for riveting the upstanding seams of sheet metal roofs, without bending or 20 injuring the seams, the machine having means for clamping or holding the seam during the riveting operation.

A still further object is the provision of a riveting machine of such construction that 25 it can rest on the roof over the seam, and the machine having manually operable means for clamping the seam and holding the rivet in place, and other manually operable means for swaging or setting the rivet.

30 It is also an object of the invention to improve the machine generally in its construction and details to enhance the utility and efficiency thereof.

With the foregoing and other objects in 35 view, which will be apparent as the description proceeds, the invention resides in the construction and arrangement of parts, as hereinafter described and claimed, it being understood that changes can be made within 40 the scope of what is claimed, without departing from the spirit of the invention.

The invention is illustrated in the accompanying drawings, wherein—

45 Figure 1 is a side elevation of the improved machine, portions being broken away.

Fig. 2 is a plan view thereof, portions being broken away and shown in section.

50 Fig. 3 is a vertical section on the line 3—3 of Fig. 2.

Fig. 4 is a horizontal section on the line 4—4 of Fig. 1.

The base or body 7 of the machine may be a casting, forging, or other suitable mem-

ber, which is formed with an arch 8 to 55 straddle the standing seam 9 of the roof, with the base seated on the roof, as seen in Fig. 1.

An anvil 10 which also serves as a clamping block or jaw, is disposed at one side of the opening of the arch, being fitted in a recess 11 with which the arch 8 is provided at said side of the opening. The anvil 10 has an extension 12 projecting away from said opening and fitted in a bore or opening 13 with which the arch 8 is provided, said opening extending from the recess 11 to the corresponding end of the base 7. A draft screw 14 is threaded into the extension 12 and has its head seated against the end of the base 7, thereby drawing the anvil 10 60 tightly into place in the recess 11. Another clamping screw 15 extends upwardly through the anvil 10 and is threaded into the arch 8 above the recess 11, thereby 65 clamping the anvil upwardly in said recess, the anvil having a cavity 16 at the bottom thereof in which the head of the screw 15 is housed. By removing the screws 14 and 15, the anvil is readily removed for 70 repair or replacement.

In order to steady and brace the base 7 when subjected to pressure, bars 17 are secured, by rivets 18 or otherwise, to the opposite sides of the base 7 at the end thereof 75 where the anvil is located, and said bars project beyond said end of the base and are bent apart to provide the diverging portions 19 which are adapted to bear on the roof, the lower edges of the bars being flush 80 with the bottom surface of the base 7. The bars 17 prevent the base being tilted laterally or toward the operator when the levers are depressed, as will hereinafter more 85 fully appear.

The anvil 10 is clamped against one side of the upstanding seam 9, to maintain the base in a fixed position relatively to the seam, during the setting or swaging of the rivet. The clamping means includes bell crank levers 20 disposed at opposite sides of the arch and fulcrumed to the base 7 by a fulcrum bolt 21 extending transversely through said levers and arch above the opening of the arch, and the depending arms of 90 said levers provide jaws 22 at opposite sides of the base and at that side of the opening of the arch opposite to the anvil 10, where-

by the jaws 22 can be swung against the side of the seam 9 opposite to the side against which the anvil or jaw 10 bears.

The jaws 22 are operated by a lever 23, which is in an inclined position above the bars 17, and which is composed of the spaced angular bars 24 having a handle 25 secured between them. The bars 24 provide a fork straddling the bars 17 and base 7, and the bars 24 are mounted on a fulcrum bolt 26 extending transversely through the bars 17 at the corresponding end of the base. The bars 24 are connected with the levers 20 by the pivot bolts 27 which are sufficiently loose to permit of relative swinging movement between the levers 23 and 20.

When the lever 23 is depressed, the levers 20 are swung to move the jaws 22 toward the anvil 10, for clamping the seam 9 between said jaws and anvil, as indicated by dotted lines in Fig. 1.

A coiled spring 28 connects the lever 23 and arch 8 to normally raise the lever so as to swing the jaws 22 away from the anvil. The ends of the spring 28 are engaged with screw eyes 29 secured in the arch 8 and handle 25, although other attaching means can be used.

The swaging or setting of the rivets is done by a cross-head or slide 30 movable in a recess 31 with which the base 7 is provided at that side of the opening of the arch opposite to the anvil 10, and said cross head or slide carries the plunger or die 32 that crushes or mashes the rivet. The plunger or die 32 is disposed between the jaws 22, and the slide 30 has a tail or extension 33 fitting slidably in a bore 34 in the base 7 extending from the recess 31 to the corresponding end of the base. A rod or seam 35 is threadedly or otherwise engaged in the extension 33 and has a nut 36 threaded on the free end thereof. The rod 35 passes between a pair of rivets 37 engaged transversely through the base 7 and extending transversely through the bore 34 beyond the extension 33. Said rivets provide a seat for a coiled spring 38 surrounding the rod 35 and confined between the nut 36 and rivets 37. The nut 36 is adjustable to regulate the tension of the spring, and the spring, as will be apparent, exerts pressure on the rod 35 to retract the plunger 32 from the rivet and seam.

In order to project the plunger 32 to swage the rivet, thrust bars 39 are disposed at opposite sides of the base 7 and their ends are seated in notches in the cross head or slide 30, as at 40. Said bars 39 have circular openings 40 in which eccentrics 42 are disposed, said eccentrics being movable with a hand lever 43 that is inclined similarly to the lever 23 above the arch. Rollers or anti-friction members 44 are disposed in the openings 41 between the ec-

centrics 42 and the thrust bars 39, to reduce friction. The lever 43 comprises the spaced bars 45 and a handle 46 secured between said bars, the bars 45 providing a fork straddling the base 7 and bars 39, and the eccentrics 42 are secured to or are a part of the bars 45. The bars 45 overlap the bars 39 and the eccentrics extend inwardly into the openings 41, as seen in Fig. 4. A pivot or fulcrum bolt extends through the bars 45, eccentrics 42 and base 7 above the bore 34 and eccentrically relatively to the openings 41 and eccentrics 42, and the arrangement is such that when the lever 43 is swung upwardly, the eccentrics 42 force the thrust bars 39 toward the anvil 10, thereby shoving the plunger 32 toward the seam and rivet. The lever 43 swings downwardly by gravity, to retract the thrust bars 39, and the spring 38 retracts the plunger 32.

The base 7 has oil ducts 48 extending downwardly to the plunger extension 33 and fulcrum bolt 47 in order that oil can be injected to lubricate said parts.

In using the machine, the rivet 49 is inserted through the seam 9 from that side at which the anvil 10 is located, and the base 7 is then slid into position to bring the anvil 10 against the head of the rivet, as seen in Fig. 1. The anvil 10 is of a size to project under the overhanging portion of the seam. The lever 23 is then depressed to bring the jaws 22 against the seam 9, thereby clamping the seam between the jaws 22 and anvil 10, with the head of the rivet held tightly between the seam and anvil. The lever 43 is then raised so that the eccentrics 42 project the plunger 32, and the plunger therefore mashes or swages the rivet at the corresponding side of the seam, to set the rivet securely in the seam. The rivet is therefore set in a convenient and efficient manner, and the swaging of the rivet is done neatly.

In applying the machine after the rivet is inserted in the aperture in the seam, the movement of the jaws 22 toward the anvil by the depression of the lever 23, will force the anvil 10 toward the seam, thereby pushing the rivet into place in the seam, and, at the same time, the seam is clamped between the jaws and anvil, thereby fixing the position of the base relatively to the seam, before the rivet is swaged. By use of the lever 43 and eccentrics 42, the plunger is moved with great force toward the anvil without excessive manual exertion, so that minimum power is necessary. It is also practically impossible for the operator to crush the rivet without first positioning the rivet properly in the seam, inasmuch as the depression of the lever 23 will not only clamp the seam between the jaws 22 and anvil, but will also force the rivet into place in the seam.

Although the machine is advantageous in connection with standing seams having flanged or overhanging portions, as shown in Fig. 1, the machine can be used for other kinds of upstanding seams.

Having thus described the invention, what is claimed as new is:—

1. A riveting machine comprising a base having a bottom surface to rest movably on sheet metal and having an opening in said surface to receive a standing seam of the metal, an anvil carried by the base to be disposed at one side of the seam, means carried by the base and operable for clamping the seam and anvil together, and rivet setting means carried by the base opposite to the anvil.

2. A riveting machine comprising a base having a bottom surface to bear movably on sheet metal and having an opening in said surface to receive a standing seam of the metal, an anvil carried by the base to be disposed at one side of the seam, clamping means carried by the base including a jaw to bear against the seam opposite to the anvil for clamping the seam between said jaw and anvil, and rivet setting means carried by the base movable toward and away from the seam at the side opposite to the anvil.

3. A riveting machine comprising a base having a bottom surface to bear movably on sheet metal and having an opening in said surface to receive a standing seam of the metal, an anvil carried by the base to be disposed at one side of the seam, a pair of jaws carried by the base and movable toward the anvil for clamping the seam between the jaws and anvil, means for operating said jaws, a rivet setting member carried by the base movable toward and away from the anvil between said jaws, and means for operating said member.

4. A riveting machine comprising a base having an arch to receive a standing seam, an anvil carried by the base at one side of the opening of the arch to be disposed at one side of the seam, levers fulcrumed to the base at the opposite sides thereof above said opening and having depending jaws to move toward and away from the anvil at the

opposite side of the seam, a hand lever fulcrumed to the base and operatively connected with said levers for swinging the jaws, a rivet setting member movable in the base toward and away from the anvil between said jaws, and means for actuating said member.

5. A riveting machine comprising a base, an anvil carried by the base, a rivet setting member having an extension slidable in the base for the movement of said member toward and away from the anvil, spring means for retracting said member from the anvil, thrust bars at opposite sides of the base and said extension having ends engaging said member, and a hand lever fulcrumed to the base having portions at opposite sides of the base operatively connected with said bars.

6. A riveting machine comprising a base, an anvil carried by the base, a rivet setting member having an extension slidable in the base for the movement of said member toward and away from the anvil, spring means for retracting said member from the anvil, thrust bars at opposite sides of the base and said extension, said member having notches in which said bars are seated at one end, and a hand lever having portions at opposite sides of the base fulcrumed to the base and provided with eccentrics, said bars being disposed between said portions and base and having openings receiving said eccentrics.

7. A riveting machine comprising a base, an anvil carried by the base, a rivet setting member carried by the base and movable toward and away from the anvil, an operating lever fulcrumed to the base and operatively connected with said member, clamping means carried by the base and movable toward and away from the anvil, an operating lever connected to the clamping means and extending upwardly from the base, and bars secured to the base and diverging therefrom to brace the base against tilting movement.

In testimony whereof I hereunto affix my signature.

ROSS A. WORKMAN.
